(57) **CLAIM**

The ornamental design for an aerial acrobatic apparatus, as shown and described.

DESCRIPTION

FIG. 1 is a top perspective view of an aerial acrobatic apparatus, showing my new design.

FIG. 2 is a bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof; and,

FIG. 9 is a top perspective view of the aerial acrobatic apparatus in a second configuration.

The broken lines show portions of the aerial acrobatic apparatus and form no part of the claimed design.

1 Claim, 9 Drawing Sheets
